UNITED STATES PATENT OFFICE.

LOUIS A. BOCKSTAHLER, OF LAKewood, OHIO.

AUTOMATICALLY-CONTROLLED FLOATING MINE.

1,221,964.

Specification of Letters Patent. Patented Apr. 10, 1917.

Application filed January 2, 1915. Serial No. 88.

To all whom it may concern:

Be it known that I, LOUIS A. BOCKSTAHLER, a citizen of the United States, and resident of Lakewood, in the county of Cuyahoga and State of Ohio, have invented 5 certain new and useful Improvements in Automatically-Controlled Floating Mines, of which I hereby declare the following to be a full, clear, and exact description, such 10 as will enable others skilled in the art to which it appertains to make and use the same.

The objects of the invention are to provide a self propelled, and automatically controlled floating mine or torpedo which is capable of attaining the following enumerated capabilities.

The several features of novelty and improvement comprise,

20 First: The employment of automatically acting stabilizers which tend to maintain the direction of the course of the mine as it passes through the water constant after it has been first established by the operator.

25 Second, the employment of instrumentalities for automatically changing the direction of the course of the mine when a predetermined distance in a straight line has been traversed, so as to cause the mine to circle 30 about its target and give it an opportunity to strike the target, in case it has passed by it while taking the direct course, thus greatly increasing the chances of finally making explosive contact with the target,

35 This is equally true if the target be stationary as a ship at anchor or in motion.

The invention also includes the combination and arrangement of parts and construction of the various details, hereinafter 40 described, illustrated in the accompanying drawings and specifically pointed out in the claims.

In the accompanying drawings Figure 1 is 45 a vertical longitudinal central section of the device; Fig. 2 is a horizontal section thereof, showing stabilizers, and operating mechanism therefor; Fig. 3 is a horizontal section through the explosive chamber; Fig. 4 is a perspective view of the stabilizer operating device, which changes the course of 50 the device; Figs. 5 and 6 show details of the cover for the air inlet opening; Fig. 7 is a longitudinal section of the exhaust pipe from the engine; Fig. 8 is a diagrammatic 55 view showing the vertical movement of the device through the water; Fig. 9 is a dia-

gram showing method of travel toward a target. Figs. 10, 11, and 12 illustrate the action of a force on the stabilizers when applied to the stern, broadside and to the bow 60 of the device respectively; Fig. 13 is a diagram illustrating the action of the timing device in opening the electric circuit which ignites the explosive.

In these drawings A is a metal shell forming 65 an inclosed hull, so shaped as to provide for the greatest amount of buoyancy compatible with lines adapted to permit the greatest freedom of movement of the device over and under the water and the maximum 70 amount of speed.

The device as shown in the drawings is provided with a powerful motor B which may be an explosive engine or any other suitable source of power, which operates a 75 propeller shaft B' and propeller B.

The propeller shaft is also employed as a source of power for other purposes among them the control of means for obtaining vertical adjustment of the device in the water 80 and for operating the means for altering the direction of movement of the device at a predetermined time or distance, as will be hereinafter further described.

In connection with the explosion engine 85 shown B² is the gasoline tank, B⁴ the starting lever and B⁵ is the exhaust pipe.

A floating valve V³ normally closes the opening. See Fig. 7.

This pipe is preferably positioned in the 90 wake of the vessel, closely adjoining the propeller B² to take advantage of the partial vacuum caused under water by the movement of the propeller. At B⁶ is shown an upwardly and downwardly extending pipe 95 through which air can be supplied at frequent intervals, to the interior of the hull whenever the vessel rises to the surface so as to furnish oxygen to the engine when an explosion engine is employed as a motor. 100

The forward end of the pipe must turn downward at B⁹ and a floating valve B¹⁰ may be used to close the opening automatically when the vessel descends underneath the water. When the motor does not require a supply of oxygen, as when electricity is employed as a motive power, a plate B⁷ can be employed to close the opening B⁸ in lieu of the pipe mentioned. 105

An important feature of the invention 110 consists in the employment of automatically acting means for maintaining a direct course

during a predetermined period of the movement of the vessel.

This means preferably comprises pivoted and weighted levers C and C' which are operatively connected with the tiller arm C²; C³ of the rudders C⁴, C⁵ that control the direction of movement of the vessel.

The levers C, C' are pivoted at c, c, and are provided at their margins with segmental gears c², c².

The lever C directly engages with a corresponding segment upon the tiller arm C² and the lever C' operates the tiller arm C³ by means of an intermediate gear or idler C⁶, since the direction of movement of the bow rudder C⁵ is the reverse of the stern rudder C⁴.

These weighted levers serve as stabilizers to preserve unchanged the direction of the vessel and only operate when force is suddenly exerted (such as the force of a wave) against one end such as the bow or stern, or against both ends simultaneously, and which without the use of the stabilizer would tend to throw the vessel out of her course.

The operation is illustrated in Figs. 10, 11, and 12 and may be described as follows:

When the vessel is subjected to a sudden shock from one side or the other, the boat will swing to accommodate the direction from which the blow may come, but the stabilizing levers will tend to remain stationary at their outer ends owing to their inertia, and being pivoted at their other ends will operate the mechanism connecting them with the respective rudders which guide the vessel.

This action is shown in Fig. 10 when a force represented by the arrow strikes broadside of the vessel. It is obvious that the bow rudder will turn to the right and the stern rudder to the left, one rudder thus counteracting the effect of the other, which action has a tendency to push the boat against the action of the force.

In Fig. 11 the force is represented as applied to the stern only and on the starboard side hence the stern rudder is placed in position to prevent the stern of the boat from being swung to port.

In Fig. 12 the force is represented as applied to the starboard side of the bow, and hence the rudder will turn to prevent the bow from being forced to port. Opposed series of springs C⁷, C⁷ return the stabilizers to their central and normal positions. The stabilizer C' must be heavier than the stabilizer C since it has a movement reverse to that of the tiller arm, and must therefore counteract the weight of the tiller in addition to its own movement.

As shown in Figs. 1, 2, 4, and 9, an important feature of the invention is found in means for altering the direct or linear course

of the vessel to a circular one at a predetermined distance from the starting point. This means permits the vessel to be aimed at a target such as a passing steamer or dreadnaught going at a predetermined rate of speed and at a computed distance from the starting point of the floating mine, and to change the direction of movement of the mine to follow the target in case it should miss the same, thus providing additional opportunity for hitting it.

The mechanism is preferably operated by the motor shaft and as shown a worm wheel D is rotated at a very slow rate of speed by means of the worm D', shaft D², the worm wheel D³ on a shaft D² and a second worm D⁴ and worm wheel D⁵ and a worm D¹⁵ upon the motor shaft. The rate of speed can be controlled by means of interchangeable gears. Upon worm wheel D is a cam D⁷ which pushes down a spring arm D⁸ which releases an arm D⁹ upon a shaft D¹⁰. The shaft is then rotated by means of a spring D¹¹ to operate the pulley sheaves D¹², D¹², over which and over guide pulleys D¹³, D¹³ the ropes D¹⁴, D¹⁴ are connected with the stabilizers C and C'. The cam D⁷ is adjustable by means of a bolt D¹⁶ and spaced holes D¹⁷ in the worm wheel D.

When the shaft D¹⁰ is released the stabilizers are pulled in opposite directions so as to bring the rudders to turn at an angle to each other so as to make the course of the vessel describe a circle of predetermined radius. The radius can be determined by means of a wheel E provided with a circular series of openings E' therein, in which a pin E² can be selectively set. This pin, as the wheel rotates, will strike against a stop E³ and limit the movement thereby limiting the movement of the rudders and their angular positions. Hence the circle of the course can be made small or large as desired and deemed most likely to reach a moving object.

The adjustment of the cam D⁷ controls the moment when the direction of the course of the vessel is changed, and the distance that the vessel travels in a direct line before the change takes place.

As shown in Fig. 9 the vessel A will take the direct course X from the shore until it reaches the path of the moving object. If it misses the object it will then take a circular course and will still have a chance of hitting the object.

As shown the intervening island Z will not present any obstruction to the path of the floating mine, if it is desired to strike the object at a point behind the island. Thus making it impossible for an enemy's ship to hide behind apparently inaccessible points.

A continuous rising and falling movement 130

is given the vessel to prevent it from floating upon the surface which would make it an accessible target to others, and from diving too deep into the water in which case it 5 would pass under its target.

This movement is exemplified by the following instrumentalities, illustrated in Fig. 1.

Here F is a shaft operatively connected 10 by a universal joint F' with the motor shaft. The outer end rests in a movable bearing F² which is supported by means of a cross rod F³ and rods F⁴, F⁵ and float F⁶ vertically movable in a perforated casing F⁷ 15 which preferably projects above the hull of the vessel.

This movable shaft is provided with a worm F⁸ which when the shaft rises engages with a segment F⁹ which operates the 20 pivoted vanes F¹⁰, F¹¹, which are shown at the sides of the vessel near the bow, in Figs. 1 and 2.

When the vessel is at the surface, as shown 25 in Fig. 8 the float will fall and the shaft will be disconnected from the segment and the vanes will be directed downwardly by means of a spring F¹¹, shown in Fig. 1, connected with the segment. When the vessel becomes immersed in the water the float will 30 rise and engage the worm and shaft and the segment will move to reverse the position of the vanes, and bring the vessel gradually to the surface. In this manner the vertical movements continue without stopping and 35 are limited in duration.

An explosive mixture R is inclosed in a chamber S in the bow of the vessel and is ignited in any desirable manner.

As shown a circuit O from a battery T 40 is closed at the terminals V, V', when a plunger W having a contact U thereon is struck by any object in the path of the vessel.

The closing of the circuit ignites the explosive. To prevent the mine from slipping by any object without igniting the explosive if struck a glancing blow, side rods H, H, are employed, connected with the plunger, and bell cranks I, I, pivoted at the sides 50 of the vessel operate the rods to move the plunger when the vessel is struck upon the side. The bell cranks are connected by means of side rails J, J, so as to be moved from any direction from which they may be 55 struck.

If the vessel should be struck upon the upper surface of the bow a rod K operatively connected with the plunger will cause the ignition of the explosive if the rod is 60 struck.

Clock controlled mechanism is employed which opens the electric circuit at a predetermined time to prevent the floating mine from becoming a menace to navigation.

65 In illustration of the action mentioned a

clock T' is shown having an hour hand T² which makes electric contact with a segment T³ and closes the battery circuit O during a predetermined number of hours, but the circuit will be open when the hand T² crosses 70 the gap in the segment.

A stop T⁴ prevents the further movement of the hand and the mine becomes harmless.

Having described the invention what I claim as new and desire to secure by Letters 75 Patent is:

1. In combination with the hull of a vessel, and steering rudders at the bow and stern thereof, of pivoted devices in said hull and operatively connected with said rudders, 80 said pivoted devices coöperating by their inertia to prevent displacement of the bow and stern of the vessel when subjected to sudden lateral shock.

2. In combination with the hull of a vessel and coöperating bow and stern rudders therefor, of horizontally swinging stabilizers operatively connected with said rudders.

3. In combination with the hull of a vessel and coöperating bow and stern rudders 90 therefor, of horizontally swinging stabilizer levers, said levers weighted at their outer ends and operatively connected with said rudders.

4. In combination with the hull of a vessel, and rudders pivoted respectively at the bow and stern thereof, of horizontally swinging stabilizing levers having weighted outer extremities, and pivoted in said hull, and gear connections between said stabilizers 95 and their respective rudders.

5. In a dirigible vessel, in combination, a hull, bow and stern rudders therefor, a tiller arm for each rudder, each arm having a gear segment thereon, a horizontally swinging 105 stabilizer having a segmental geared edge and engaging with the gear segment upon said stern tiller arm, a similar horizontally swinging stabilizer for the said bow rudder, and an idler operatively connecting said bow 110 tiller and stabilizer, said stabilizers weighted, and the bow stabilizer additionally weighted to overcome the weight of the tiller arm for the bow rudder.

6. The combination with the hull of a 115 vessel and bow and stern rudders, and horizontally moving stabilizers therefor, of means for propelling the vessel at a predetermined rate of speed, and means for automatically moving said stabilizers to change 120 the direction of movement of said vessel after a predetermined distance has been traversed by said vessel, said means for moving said stabilizers operatively connected with said propelling means.

7. The combination with the hull of a vessel and bow and stern rudders therefor, of stabilizing devices operatively connected with said rudders to normally retain the 125 course of the vessel in a straight line, and 130

automatically acting means for moving said stabilizers to deflect said vessel from her course.

8. The combination with the hull of a vessel, stern and bow rudders, and stabilizing devices therefor, operatively connected therewith, and a source of power, of a device for operating said stabilizers jointly to change the course of the vessel, and means for automatically and operatively connecting said source of power with said stabilizer operating device, at a predetermined position of said vessel.

9. In combination with the hull of a vessel, bow and stern rudders therefor, stabilizers for controlling the movements of said rudders, and a propeller shaft, of a shaft parallel thereto, a loose disk thereon, means

for rotating said loose disk at a low rate of speed, said means operatively connected with said propeller shaft, a separate means for rotating said shaft, a retaining means for said shaft, means operatively connected with said disk for releasing said retaining means to liberate said shaft, and means operatively connecting said parallel shaft and stabilizers for moving the same to change the course of the vessel when said shaft is released, substantially as described.

In testimony whereof, I hereunto set my hand this 24th day of December 1914.

LOUIS A. BOCKSTAHLER.

In presence of—

RALPH W. JEREMIAH,
Wm. M. MONROE.
